PILLOW DOLL

Pauline H. van Laar, Pasadena, Calif.

Application November 13, 1951, Serial No. 17,356

Term of patent 7 years

(Cl. D34—2)

To all whom it may concern:

Be it known that I, Pauline H. van Laar, a citizen of Switzerland, residing at Pasadena, in the county of Los Angeles and State of California, have invented a new, original, and ornamental Design for Pillow Doll, of which the following is a specification, reference being had to the accompanying drawing, forming part thereof.

Fig. 2 is a side view of the same.

Fig. 3 is a back view of the same, and

Figs. 4, 5 and 6 are bottom, top and side views, respectively, showing the doll as it appears when folded as a pillow.

I claim:
The ornamental design for a pillow doll, as shown.

PAULINE H. VAN LAAR.
